CLAIM

The ornamental design for a video router as shown and described.

DESCRIPTION

FIG. 1 is a perspective view of a video router showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions depicted in dashed broken lines and the portions depicted within dashed broken lines depict portions of the video router which form no part of the claimed design.

1 Claim, 6 Drawing Sheets
